UNITED STATES PATENT OFFICE.

HARRY CRAVEN, OF PITTSFIELD, ILLINOIS.

GUN-SILENCER.

984,750.

Specification of Letters Patent. Patented Feb. 21, 1911.

Application filed February 1, 1910. Serial No. 541,285.

To all whom it may concern:

Be it known that I, HARRY CRAVEN, citizen of the United States, residing at Pittsfield, in the county of Pike and State of Illinois, have invented certain new and useful Improvements in Gun-Silencers, of which the following is a specification.

My invention relates to means for deadening or silencing the noise due to the firing 10 of a gun, and particularly to a device adapted to be attached to the barrel of a gun and which shall, while permitting the passage of the projectile, prevent the passage of gas through the muzzle of the gun, the gas 15 being directed into a muffler, and thence passing out to the atmosphere.

My invention contemplates forming or 20 providing the muzzle of a gun with a valve which is supported upon a spring and which normally closes the muzzle of the gun, this 25 spring being so arranged that as the projectile passes out, the spring will be raised, lifting the valve and permitting the escape of the projectile, the spring returning the 30 valve to its original position as soon as the projectile has left the muzzle of the gun, thus confining the gas within the gun barrel. The gun barrel or the barrel section attached thereto is provided with a plurality 35 of perforations permitting the escape of the gas, and the forward end of the barrel or the barrel section attached thereto is provided with a chamber having perforations leading to the outer air, into which chamber the gas passes from the gun barrel.

For a full understanding of the invention and the merits thereof, and to acquire a knowledge of the details of construction, reference is to be had to the following description and accompanying drawings, in 40 which:

Figure 1 is a perspective view of my silencer applied to a single-barreled gun. Fig. 2 is a longitudinal sectional view thereof; Fig. 3 is a perspective view of my invention as applied to a double-barreled gun; Fig. 4 is a longitudinal section of Fig. 3, through one of the barrels; Fig. 5 is a transverse section on the line 5—5 of Fig. 4; Fig. 6 is a transverse section on the line 6—6 of Fig. 4; Fig. 7 is a longitudinal section of a gun barrel, showing my silencer formed in part therewith; Fig. 8 is a perspective view showing a modified form of

silencer, as applied to a single-barreled gun; 55 Fig. 9 is a like view showing another modification; and, Fig. 10 is a transverse section through the auxiliary barrel and the muffler and looking toward the forward end of the auxiliary barrel and muffler. 60

Corresponding and like parts are referred to in the following description and indicated in all the views of the drawings by the same reference characters.

Referring to Figs. 1 and 2, A designates 65 a gun barrel of any usual or ordinary kind, having a sight B. 2 designates an auxiliary barrel section which is adapted to fit over the muzzle of the barrel, it being enlarged at 3, to that end, the enlarged portion being 70 countersunk for the reception of the muzzle of the gun and having such proportion that the inner surface of the barrel is practically continuous with the inner surface of the auxiliary section. The portion of the auxiliary barrel which fits over the muzzle of the gun is reinforced, as at 4, and the upper portion of the auxiliary barrel is split or slotted, as at 5, to permit the auxiliary barrel 75 to be placed on over the sight B, the sight being received within said slot 5. The auxiliary barrel is held upon the gun barrel by means of set screws 6 or other like devices which will hold it firmly in place. The forward end of the auxiliary barrel is provided 80 with a spring 7 which is attached at its rear end to the inner face of the barrel, preferably in a groove therein, so that the face of the spring shall be flush with the face of the barrel, this groove 8 being continued to the 85 forward end of the auxiliary barrel. The spring extends forward and downward and its lower end is received in a groove 9 formed in the lower portion of the barrel at its forward end. The end of the spring is 90 angularly bent, as at 10, and attached to this angular bend is the disk-like valve 11 which is adapted to fit snugly against the end of the auxiliary barrel and close the same. The lower portion of the auxiliary 100 barrel is provided with a plurality of rearwardly inclined perforations 12 opening into a chamber 13 which is preferably cylindrical and which is formed to surround the auxiliary barrel 2 or form part thereof. The 105 ends of this chamber 13 are closed by end plates 14, these plates being perforated, as at 15, either at one or both ends, preferably,

however as shown, at one end. The extremity of the auxiliary barrel 2 is provided with the upwardly projecting sight 16 which is to be used in conjunction with the usual sight 5 B of the gun.

The parts of my device are to be formed of steel and aluminium, the chamber 13 being of the latter metal, inasmuch as it will be subjected to comparatively slight strain, 10 and it is sufficiently light not to overweight the barrel of the gun.

In Fig. 1, as above described, I have shown my invention as applied to a single-barreled gun. The silencer for double-barreled guns is practically the same as that for 15 single barrels. This form of the invention is shown in Fig. 3, wherein A A designates the barrels of the gun, and B the sight therefor located midway between the barrels. 20 The silencer comprises two auxiliary barrels 2 divided from each other by the longitudinal partition 18. This partition only extends slightly rearward of the chamber 13, the barrels both merging into each other 25 beyond this point, and the exterior bore thereof being sufficiently enlarged to permit the reception of gun barrels, the inner surfaces of the gun barrels being flush with the inner surfaces of the auxiliary barrels. The 30 rear ends of the auxiliary barrels are slotted, as at 5^a to accommodate the sight B, the upper edge of the partition plate 18 forming the continuation of the middle rib C of the gun and being provided at its extremity 35 with the sight 16^a. The chamber 13 has exactly the same construction as the silencing chamber before described, and is formed preferably in one piece with the auxiliary barrels 2. The auxiliary barrels are formed 40 with perforations 12 which open into the chamber 13, and the chamber itself is provided with perforations 15 through one wall thereof. The valve 11 and spring 7 are formed as previously described, the springs 45 being received in grooves 8 and 9 on the inner surface of the barrel.

While in the figures previously described I have shown an embodiment of the principles of my invention in which auxiliary barrels are used, which are attached to the main barrels of the gun, I do not wish to be limited to this, as it will be obvious that I might form the muzzle of the main barrel itself 50 with perforations, and apply my silencing device thereto, as shown in Fig. 7. In this figure, the barrel of the gun is designated A' and the muzzle is provided with the perforations 12^a which open into the silencing chamber 13 which is constructed precisely as 55 heretofore described. The valve is also the same as that previously described, and merely differs in that it is attached to the muzzle of the gun, instead of to the auxiliary barrel, the muzzle of the gun being 60 grooved upon its inside face, as previously 65

described, for the auxiliary barrel to receive the valve spring when the valve is opened. It will be seen that the construction shown is precisely the same as that heretofore described, except that the silencer 70 is formed with the gun and not as an attachment thereto.

In Fig. 8 I show another modified form of my invention, as applied to a single-barreled gun wherein the construction is similar to that shown in Fig. 3. In Fig. 8, 20 designates the auxiliary barrel which is enlarged at its rear end, as previously described and is attached to the gun barrel precisely as described in the construction 80 illustrated in Fig. 1. The auxiliary barrel 20 is slotted at its rear end, as at 21, to fit over the sight B on the barrel A, and the forward end of the auxiliary barrel is provided with a sight 22. The forward end of 85 the auxiliary barrel is also provided with a valve 23 which is attached to the end of a spring precisely like the spring 7 shown in Fig. 4 and whose upturned end 25 is attached to the outer face of the valve, as 90 shown in Fig. 8. The valve is intended to rise as the shot is fired. In this form of my invention, the muffler 26 instead of extending entirely around the auxiliary barrel, as in Fig. 1, only partially surrounds the 95 auxiliary barrel and is riveted or screwed thereto, as at 27.

In Figs. 9 and 10, I show still another form of muffler attached to an auxiliary barrel. In these figures, 30 designates the auxiliary 100 barrel enlarged at its rear end for the reception of the muzzle of the barrel A, and slotted, as at 31, to accommodate the sight B. The forward end of the auxiliary barrel is formed with a fore-sight 32 and attached to 105 the auxiliary barrel is a muffler 33. The opposed margins of the side walls of the muffler are bent around to fit closely against the auxiliary barrel, as indicated at 33^a and are riveted or otherwise attached thereto, as 110 at 34. It will be seen that this form of muffler acts to reinforce the auxiliary barrel and makes the construction particularly strong. While I have heretofore described the valve at the end of the auxiliary barrel 115 as opening upward, it is to be understood that it may equally well open downward, and this construction is shown in Figs. 9 and 10, wherein the valve 36 is attached to a spring 35 which at its rear end is attached 120 in a slot formed in the lower portion of the barrel, the slot being indicated by the numeral 38, and then extends upward and forward to the muzzle, where it is angularly bent, as at 39 and is then attached to the 125 barrel 36. This valve operates in precisely the same manner as the valves previously described except that it moves downward as the charge passes out of the barrel instead of moving upward. The perforations extend- 130

ing from the barrel to the muffler are slanted rearward and downward in order to prevent shot from entering the gas chamber in their passage out of the barrel.

5 While I have shown my improved silencer as including both a valve and a muffler, I wish it understood that the muffler may be used alone without the valve, and in some degree secure the result aimed at by my 10 invention.

The operation of my invention is as follows: The spring normally holds the valve down snugly against the forward end of the gun barrel, as shown in Fig. 3. When 15 the charge is fired, the wadding is driven out and will force the spring upward, thus raising the valve from the end of the auxiliary barrel, the spring moving up into the groove in the barrel, so that the face of the spring 20 is flush with the inside face of the auxiliary barrel. As soon as the solid portion of the charge has passed out, the spring will retract the valve, which will cover the end of the auxiliary barrel, preventing the escape 25 of gases therethrough. The gases thus forced back, will find an outlet through the perforations into the muffling chamber, and will thence pass out to the outer air through the perforations in the end will thereof. 30 Exactly the same operation takes place with the double-barreled gun as with the single. It is of course to be understood that the muffling chamber shall be of a capacity sufficiently great to receive the gases forced out 35 of the gun, without any danger of its being burst. The muffling chamber is of such size that the gas will be greatly reduced in pressure when it passes into the chamber, and hence will pass into the open air at a com- 40 paratively slight pressure, thus preventing any sound other than a slight hissing noise.

Having thus described the invention, what I claim is:—

1. A gun barrel having perforations in its 45 muzzle, a gas chamber into which said perforations open, a disk-shaped valve normally disposed against the outer end of the barrel and closing the same, and a spring attached at one end to the barrel and at its 50 free end to the valve and permitting the valve to move transversely of the axis of the barrel.

2. A gun silencer including a barrel having perforations in its muzzle, a gas chamber 55 into which said perforations open, a disk-shaped valve normally disposed against the outer end of the barrel and closing the same, and a spring attached at one end to the interior of the barrel and at the other end to 60 the valve, said spring extending diagonally across the interior of the barrel in the path of movement of the charge and in position to be struck by the charge and raised as the charge passes out of the barrel.

65 3. A gun barrel having perforations at its

muzzle end and formed with a longitudinal groove, a spring mounted in one end of said longitudinal groove and extending diagonally across the diameter of the barrel to the open end thereof, and a valve normally supported by said spring in front of the muzzle and closing the same.

4. A gun barrel having perforations in its wall, at its muzzle end, a gas chamber located at the muzzle, into which said perforations open, said chamber having openings to the outer air, a spring located in the interior of the barrel at the muzzle end, said spring being attached at one end to the inside face of the barrel and extending diagonally across the barrel to the mouth thereof, and a disk-like valve supported on said spring and normally closing the opening in the barrel.

5. A gun barrel having perforations in its wall, at its muzzle end, a gas chamber attached to the muzzle of the barrel, into which said perforations open, said chamber having openings leading to the outer air, the interior of the barrel having a longitudinal groove extending to the open end of the barrel and having a groove at its end, opposed to the first named groove, a spring attached at one end in the first named groove and extending diagonally across the barrel and normally fitting into the second named groove, and a disk-like valve supported on said spring and normally closing the opening in the barrel.

6. A silencing attachment for guns, including a barrel adapted to be attached to the muzzle of a gun and form a continuation of the gun barrel, the barrel of the attachment being perforated and provided with a longitudinal groove at its muzzle end, a spring supported at one end in the inner end of said longitudinal groove, said spring extending transversely across, upward and forward to the end thereof and projecting beyond the muzzle thereof, a disk-like valve attached to the end of the spring and normally held thereby against the opening of the barrel, and a gas chamber attached to the auxiliary barrel, into which said perforations open, said chamber being provided with openings leading to the outer air.

7. A silencing attachment for guns, comprising auxiliary barrels adapted to fit over the muzzle of a double-barreled gun and be clamped thereon, the interior face of each auxiliary barrel being formed with a groove longitudinally extending to the extremity of the auxiliary barrel, a spring mounted at its inner end in the inner end of each groove and extending forward and across the barrel to the open end thereof, a valve supported on the end of each spring and adapted to close against the mouth of the auxiliary barrel, and a gas chamber mounted on the auxiliary barrels, into which the perfora- 130

tions thereof open, said chamber being provided with perforations opening to the outer air.

8. A silencing attachment for double-barreled guns, comprising two parallel auxiliary barrels having a socket at their inner ends adapted to fit over the muzzles of a double-barreled gun, said socket being slotted to accommodate the forward sight of said gun, each of the auxiliary barrels having a longitudinal groove formed on its inside face, extending to the open end of the barrel, a valve for each auxiliary barrel, adapted to close against the open end thereof, a spring for each valve, attached at its

forward end thereto and crossing said barrel and attached at its rear end in the rear end of the groove, and a gas chamber attached to the auxiliary barrels, the wall of each auxiliary barrel being perforated to permit the 20 passage of gas into the gas chamber, said gas chamber being formed with openings leading to the outer air.

In testimony whereof I affix my signature in presence of two witnesses.

HARRY CRAVEN. [L.S.]
